US00D808013S

(12) **United States Design Patent** (10) **Patent No.:** **US D808,013 S**
(45) **Date of Patent:** **** Jan. 16, 2018**

(54) **CATHETER**

(71) Applicant: **Smiths Medical ASD, Inc.**, Plymouth, MN (US)

(72) Inventors: **Harsh D. Chheda**, Cheshire, CT (US); **Kathryn Felicito**, Cheshire, CT (US); **Christopher Roehl**, New Hartford, CT (US)

(73) Assignee: **Smiths Medical ASD, Inc.**, Plymouth, MN (US)

(**) Term: **15 Years**

(21) Appl. No.: **29/582,452**

(22) Filed: **Oct. 27, 2016**

(51) LOC (11) Cl. **24-02**

(52) U.S. Cl.

USPC **D24/130**

(58) **Field of Classification Search**

Pedersen, P.A.

(57) **CLAIM**

We claim the ornamental design for a catheter, as shown and described.

DESCRIPTION

FIG. 1 is a top perspective view depicting a catheter.

FIG. 2 is a top view thereof.

FIG. 3 is a bottom view thereof.

FIG. 4 is a right side view thereof.

FIG. 5 is a left side view thereof.

FIG. 6 is a rear view thereof; and,

FIG. 7 is a front view thereof.

The broken lines depict portions of the catheter that form no part of the claim.

1 Claim, 3 Drawing Sheets
